(57) **CLAIM**

The ornamental design for a folding knife, as shown and described.

DESCRIPTION

FIG. 1 is a perspective view of a folding knife, showing my new design;

FIG. 2 is a right-side elevation view thereof;

FIG. 3 is a left-side elevation view thereof;

FIG. 4 is a top plan view thereof;

FIG. 5 is a bottom plan view thereof;

FIG. 6 is front elevation view thereof;

FIG. 7 is a rear elevation view thereof; and,

FIG. 8 is a perspective view thereof, wherein the replaceable blade element is positioned separate from the knife.

The broken lines depict portions of the folding knife in which the design is embodied that form no part of the claimed design.
